UNITED STATES PATENT OFFICE.

JENS THEODOR SUHR SCHOUBOE, OF HOLTE, DENMARK.

FRAME FOR PACK-SADDLES.

No. 868,019.

Specification of Letters Patent.

Patented Oct. 15, 1907.

Application filed February 23, 1906. Serial No. 302,434.

To all whom it may concern:

Be it known that I, JENS THEODOR SUHR SCHOUBOE, a subject of the King of Denmark, residing at Holte, Denmark, have invented new and useful Im-
5 provements in Frames for Pack-Saddles, of which the following is a specification.

The invention relates to an improved frame for pack saddles to be used with horses, mules, or other animals in the transportation of goods.

10 The object of the invention is to provide a frame so constructed as to facilitate the placing and removal of goods to be transported, the invention also providing a frame of simple and durable construction.

According to my invention the most desirable embodiment embraces the arrangement of the goods to be transported in pairs of receptacles of approximately equal weight and connected by a supporting strap or the like and to this end the invention consists in the provision of a frame wherein there is provided a sup-
15 porting member over which said straps may be thrown and on which they may be secured, the goods depending from said straps on both sides of the animal and serving to balance the weight. To this end the said frame consists of a supporting member which is main-
20 tained out of engagement with the back of the animal on which the saddle is disposed, there being provided lateral portions adapted for engagement with the sides of the animal, said lateral portions being so disposed and formed as to rest upon the back of the animal but
25 preferably at one side of the center thereof, the central supporting member being maintained in an elevated position by connecting the lateral portions with the central supporting member in such a manner as to prevent the lateral members spreading beyond a prede-
30 termined point.

The invention will be more fully described in connection with the drawing and will be more particularly set forth and ascertained in and by the appended claims.

In the drawings:—Figure 1 is a view in side elevation of a frame for pack saddles embodying the main features of my invention. Fig. 2 is an end elevation thereof. Fig. 3 is a longitudinal section of a portion of the upper supporting member showing a device for retaining in position the supporting straps of the goods in
45 transport. Fig. 4 is a section on line I—I of Fig. 3.

Like characters of reference designate similar parts throughout the different figures of the drawing.

As shown, the improved frame consists of a main supporting member or middle-tree *a*, which is curved
50 upwardly in the direction of its length to conform to the curvature of the back of the transport animal, the curvature being gradual toward the center and

increasing toward the ends. It will be obvious, however, that where relatively short frames are used the curvature of the main supporting member will be varied accordingly. The middle-tree *a* is preferably of hollow construction being formed of sheet metal bent upon itself laterally in the manner shown in Fig. 2. There are provided, as shown, lateral or side-trees *b* also formed of sheet metal and preferably disposed in parallel relation with respect to the middle-tree *a* and being of substantially the same length. Said side-trees *b* are connected with the middle-tree by straps or plates *d* which, as shown, are three in number and are preferably formed of a yielding material and are curved inwardly from their points of juncture with the trees *b* to the tree *a*. As shown, said straps *d* are formed of single strips of metal, the outer free ends of which are riveted or otherwise secured to the trees *b*, the central portions being bent to project between the lateral walls of the middle-tree *a*, in a manner to be anchored thereto. The side-trees *b* form a continuous bearing surface adapted to engage the back of the animal laterally of the center thereof and the straps *d* prevent the lateral trees from spreading beyond a predetermined point in a manner to hold the saddle in place. This construction avoids the necessity of supporting the lateral trees *b* in position. The lateral trees *b* are provided with clips *c* for securing the girths whereby the saddle is strapped in place and there is also provided clips *k* adapted to receive straps or other securing means whereby the goods in transport may be prevented from swinging laterally while the animal is walking or running.

In the use of a saddle made according to my invention the goods are disposed in receptacles or bags connected by straps, one of the bags being thrown over the middle-tree and the strap thereof being secured in place preferably near the center thereof. Means are provided whereby the straps may be secured in a manner to prevent the bags from being longitudinally and vertically displaced, said means consisting, as shown, of levers *f* pivotally mounted to standards *e* rising from the middle-tree *a*.

The straps are preferably apertured or provided with rings adapted to be threaded on said levers *f* or the said straps may be impinged between the levers *f* and the middle-tree *a*. There are provided springs *g* which are connected to the levers *f* at one side of the pivotal mounting thereof, said springs being anchored to any suitable stationary parts such, for instance, as a cross-bar *h* secured to the middle-tree *a* as clearly shown in Figs. 3 and 4. When the lever *f* is thrown rearwardly so that the mounting of

the spring is shifted beyond the pivotal mounting, the spring serves to lock the lever in its rearward position and, when the lever is thrown into the position shown in Figs. 3 and 4, the spring serves to retain said lever in such position.

I claim:—

1. A frame for pack saddles comprising in combination, a middle tree formed of sheet material of U-shaped cross section, said tree being curved upwardly in the direction 10 of its length, said curve being gradual near the center and increasing near the ends, side trees, a plurality of inwardly curved straps connecting said middle and side trees and maintaining said middle tree out of engagement with the back of the animal, and spring actuated fastening means 15 on said middle tree.
2. A frame for pack-saddles comprising a middle-tree,

a rotatable lever mounted thereon, adapted to retain the load of said saddle in position.

3. A frame for pack-saddles comprising a middle-tree, a plurality of rotatable levers mounted thereon adapted to 20 hold the load in position, and springs for maintaining said levers in the position to which they are rotated.

4. A frame for pack saddles comprising in combination, a middle-tree, rotatable levers mounted thereon, side trees, and three inverted U bars connecting said middle and 25 side trees and maintaining the former out of engagement with the back of the animal.

In testimony whereof I have signed my name to this specification in the presence of two subscribing witnesses.

JENS THEODOR SUHR SCHIOUBOE.
